(57) **CLAIM**

I claim the ornamental design for a hand shower, as shown and described.

DESCRIPTION

FIG. 1 is a top perspective view of a hand shower showing my new design;

FIG. 2 is a bottom perspective view of the hand shower of FIG. 1;

FIG. 3 is a front view of the hand shower of FIG. 1;

FIG. 4 is a rear view of the hand shower of FIG. 1;

FIG. 5 is a left side view of the hand shower of FIG. 1;

FIG. 6 is a right side view of the hand shower of FIG. 1;

FIG. 7 is a top view of the hand shower of FIG. 1; and,

FIG. 8 is a bottom view of the hand shower of FIG. 1.

The broken lines in FIGS. 1-8 are for environmental purposes only and form no part of the claimed design.
